METAL PANEL FENCE

Thomas M. Daniel, Birmingham, Ala.

Application September 25, 1950, Serial No. 186,633

14. Claims. (Cl. 256—21)

1

This invention relates to metal fences and has for an object the provision of a fence made of metal posts and sheet metal panels, the edges of the panels being provided with continuously extending, rounded sections, preferably formed integrally with the panels, thus eliminating the danger of injury to stock enclosed by the fence and adding strength to the panels, permitting them to be made of a relatively light sheet.

A further object of my invention is to provide a fence of the character designated in which the parts thereof may be fabricated in the shop and easily erected by unskilled labor, thus providing a fence which is economical to manufacture and install.

A still further object of my invention is the provision of a sheet metal fence which lends itself to mass production and one which may be coated with baked on enamel after the post and panels are formed and the holes punched therein thus resulting in a rust resisting fence and one having a pleasing appearance.

As is well known in the art to which my invention relates, live stock, particularly horses, are often injured by the sharp edges generally resulting from the construction of a fence of boards and by the barbs on wire fences. Even minor injuries oftentimes become serious due to infection. To overcome these difficulties, I have devised a sheet metal fence which prevents the escape of animals, one which is free from barbs and sharp edges and a fence which is durable and strong.

A metal fence embodying features of my invention is illustrated in the accompanying drawing forming a part of this application, in which:

Fig. 1 is an elevational view of the fence;

Fig. 2 is a sectional view on an enlarged scale taken along the line II—II of Fig. 1;

Fig. 3 is a sectional view on an enlarged scale taken along the line III—III of Fig. 1 and showing panels in which the reinforcing bead of one end is pinched and the other is unpinched;

Fig. 4 is an enlarged perspective view partly broken away and showing the upper panels secured to the post;

Fig. 5 is an elevational view on an enlarged scale showing the upper panel members in abutting relation and showing the post in dotted lines;

Fig. 6 is a view on an enlarged scale similar to Fig. 5 showing the ends of the lower panels;

Fig. 7 is an elevational view of the fence embodying a cylindrical post, partly broken away and in section;

2

Fig. 8 is a sectional view taken along the line VIII—VIII of Fig. 7;

Fig. 9 is an elevational view of the fence embodying a rectangular post, partly broken away and in section;

Fig. 10 is a sectional view taken along the line X—X of Fig. 9 showing the ends of the panels abutting within the post;

Fig. 11 is a view similar to Fig. 10 showing the ends of the panels overlapping within the post; and,

Fig. 12 is an elevational view of the fence as shown in Fig. 1 with one of the post channel members removed and showing the panels inclined to one another, as for instance when there is a change in slope of the ground between panels.

Referring now to the drawings for a better understanding of my invention, I show, in Fig. 1 a fence comprising posts 10 which, as shown in Fig. 3 may be in the form of oppositely disposed metal channels 11 and 12 with their legs 13 and 14 turned toward each other. The adjacent ends of the legs 13 and 14 are outturned to provide flanges 15 and 15a. The post may have any desired dimensions. In practice I find that a post comprising channels approximately 2 inches wide having legs approximately $\frac{1}{2}$ inch in length and outwardly extending flanges approximately $1\frac{1}{8}$ inches wide is satisfactory in every respect. The channels may be formed of sheet metal of 18 to 12 gauge.

Extending between the posts 10 are upper rail rail or panel members 16 and lower rail or panel members 17. The panels 16 and 17 are formed from sheet metal and have the longitudinal edges thereof rolled to form integrally therewith edges or beads 18 which are circular in cross section, as clearly shown in Figs. 2 and 4. The rolled edges 18 form reinforcing beads which greatly increase the strength of the panels and define therebetween a flat intermediate portion 19. The panels 16 and 17 may also be of any desired width. Preferably, I employ panels approximately 6 inches wide having rolled edges approximately $1\frac{1}{8}$ inches in diameter and an intermediate portion 19 approximately $4\frac{1}{2}$ inches wide. Likewise I prefer to roll the edges or beads 18 so that they are centered relative to the plane of the panels as viewed in transverse section.

The ends of the upper panels 16 are shaped as shown in Fig. 5 so that when assembled the upper rolled edge 18 extends to the center of the posts 10. The portion 19 of the panel 16 intermediate the rolled edges 18 is formed so that it fits between the flanges 15 or 15a as the case may be;

and terminates adjacent the inner edges of the legs 13 or 14 of the channels. The lower rolled edge 18 of the panel 16 terminates adjacent the outer edge of the flanges 15 or 15a.

The ends of the lower panels 17 are shaped as shown in Fig. 6 so that when assembled the ends thereof intermediate the rolled edges 18 extend between the flanges 15 or 15a, as the case may be, and terminate adjacent the inner edges of the legs 13 or 14 of the channels. Both upper 10 and lower rolled edges 18 of the panels 17 terminate adjacent the outer edge of the flanges 15 or 15a. The ends of the rolled edges may be pinched as at 20 or be left circular as shown at 20'.

To secure the panels 16 and 17 to the post 10 and provide means for erecting a fence having one portion inclined to the other as shown in Fig. 12, elongated openings 21 are provided in the projecting ends of the intermediate portions of the panels. The openings extend longitudinally of the panel and, for the post and panels described above, should be approximately $\frac{7}{16}$ of an inch in length and approximately $\frac{1}{4}$ of an inch in width. Also, I have found that openings approximately $\frac{1}{8}$ of an inch from the lateral sides of the portion 19 and approximately $\frac{1}{4}$ of an inch from the ends of the panel portion 19 are satisfactory in every respect. Vertically spaced openings 22 are provided in the flanges 15 and 15a for receiving bolts 23 having nuts 24 therefor. The bolts pass through the opening 21 thus securing the panels to the posts. It will be apparent that by providing the elongated openings 21 in the ends of the panels the opposite end thereof may be raised or lowered in relation to the post.

The post 10 may be reinforced by securing channel members 25 within the lower portion of the channels 11 and 12. I have found in actual practice that the channels 11 and 12 may be made from approximately 18 gauge sheet metal where the reinforcing members 25 are employed. Where the reinforcing members are not employed the channels should be of approximately 14 gauge sheet metal. Also, the panels 16 and 17 should be of approximately 18 gauge sheet metal.

The upper portion of channel members 11 and 12 forming the posts may be pinched inwardly as at 28 so that the upper edges of the channels lie beneath and wholly within the confines of the rolled edges 18, the diameter of the rolled edges 18 being as great or greater than the width of the pinched upper end of the post. The construction described provides a continuous smooth upper surface for the fence thus preventing injury to the necks of live-stock.

The post 10 and panels 16 and 17 are fabricated in the shop and a protective coating such as baked enamel applied. This coating is applied after all the members are cut and rolled to shape and all holes punched, thus assuring that all surfaces are coated with the enamel.

From the foregoing the method of fabricating and erecting my improved sheet metal fence may now be readily understood. The post 10 is formed by bringing together the channels 11 and 12 with the flanges 15 and 15a facing each other. The post is then anchored to the ground 26 by forming a concrete block 27 about the lower portion thereof or in any other suitable manner. The ends of the panels 16 and 17 are then placed between the flanges 15 and 15a by springing the channels apart slightly and secured thereto by means of the bolts 23.

A slightly modified form of my invention is illustrated in Figs. 7 and 8 of the drawing in 75

which I employ a post 29 in the form of a cylindrical tube. Oppositely disposed slots 31, slightly greater in length than the width of the portion 19 of the panels are provided in the sides of the post for receiving the ends of the panels 16 and 17. The projecting ends of the central portions 19 overlap each other within the cylindrical post 29 and are secured to the post by means of bolts 32 having nuts 33 therefor.

In Fig. 9 of the drawing I show a still further modified form of my invention in which a rectangular tubular post 34 is employed. Oppositely disposed slots 31a are provided in the sides of the post 34 for receiving the ends of the panels 16 and 17. The projecting ends of the panels 15 may overlap within the post, as shown in Fig. 11 and may be secured to the post 34 by means of a single pair of bolts 32. If desired, the ends of the panels may abut each other, as shown in Fig. 10, and be secured to the post 34 by means of two pairs of the bolts 32.

From the foregoing it will be seen that I have provided a sheet metal fence which may be fabricated in the shop and erected with minimum difficulty. By providing the rolled edges on the panels the strength of the panels is greatly increased and there is no danger of live-stock being injured by coming in contact with the fence. While I have described bolts and nuts for assembling the fence, it may be assembled by means of rivets, snap fasteners and the like.

While I have shown my invention in several forms, it will be obvious to those skilled in the art that it is not so limited, but is susceptible of various other changes and modifications without departing from the spirit thereof, and I desire therefore, that only such limitations shall be placed thereupon as are specifically set forth in the appended claims.

What I claim is:

1. In a sheet metal fence, posts comprising oppositely disposed channels with their legs facing each other and having outturned flanges extending normal to the ends of the legs of said channels, vertically spaced panels between the posts with the ends thereof between said outturned flanges, longitudinally extending rolled edges circular as viewed in transverse section on said panels, the upper rolled edges of adjacent upper panels extending over the top of the post therebetween and substantially abutting each other, the remaining rolled edges of said panels terminating at the outer edge of said outturned flanges, and means securing the panels to the flanges.

2. A sheet metal fence as defined in claim 1 in which the channels are tapered inwardly at the upper end of the post, the upper end of said post being slightly less in thickness than the external diameter of the upper rolled edges of the panels overlying the upper end of the post.

3. A sheet metal fence as defined in claim 1 in which there are channel reinforcing members nested within and secured to the lower portion of the post channels.

4. A sheet metal fence as defined in claim 1 in which the portions of the panels between the flanges are the portions thereof intermediate the rolled edges.

5. In a sheet metal fence as defined in claim 1 in which the rolled edges are centered relative to the plane of the panels as viewed in transverse section.

6. In a sheet metal fence, posts comprising oppositely disposed channels with their legs facing each other and having outturned flanges at the

outer edges of the legs of said channels, upper and lower vertically spaced panels having continuous longitudinally extending rolled edges circular as viewed in transverse section, the upper rolled edges of adjacent upper panels extending over the top of the post therebetween and substantially abutting each other in endwise relation, the remaining rolled edges of the upper and lower panels terminating at the outer edges of the outturned flanges, end portions on the panels intermediate the rolled edges thereof between the outturned flanges of the channels, there being openings in said end portions between the flanges and in the outturned flanges of the posts, and bolts extending through said openings securing the panels to the post flanges.

7. A sheet metal fence as defined in claim 6 in which the openings in the end portions of the panels are elongated longitudinally of the panels.

8. In a sheet metal fence, posts, each comprising a cylindrical tube having vertically extending oppositely disposed slots therein, panels having longitudinally disposed rolled edges circular as viewed in transverse section extending between said posts, the upper rolled edge of adjacent top panels extending over the top of the post therebetween and substantially abutting each other, the remaining rolled edges of the panels terminating at the outer edge of the post, the end portions of said panels between said rolled edges being in said slots, and means securing the panels to the post.

9. A sheet metal fence as defined in claim 8 in which the means securing the panels to the post comprises a bolt extending through said post and the ends of said panels.

10. A sheet metal fence as defined in claim 8 in which the end portions of the panels overlap each other within the cylindrical tube.

11. In a sheet metal fence, posts, each comprising a rectangular tube having vertically extending oppositely disposed slots therein, panels having longitudinally extending rolled edges circular as viewed in transverse section extending

between said posts, the upper rolled edges of adjacent top panels extending over the top of the post therebetween and substantially abutting each other, the remaining rolled edges of the panels terminating at the outer edge of the post, the end portions of said panels between said rolled edges being in said slots, and means securing the panels to the post.

12. A sheet metal fence as defined in claim 11 in which the end portions of the panels overlap each other within the rectangular tube and are secured to the post by means of a bolt extending through said post and the ends of said panels.

13. A sheet metal fence as defined in claim 11 in which the end portions of the panels substantially abut each other within the rectangular tube and are secured to said tube by means of bolts passing through the tube and the ends of said panels.

14. In a sheet metal fence, posts having vertically extending oppositely disposed openings therein, panels having longitudinally extending rolled edges circular as viewed in transverse section, the upper rolled edges of adjacent upper panels extending over the top of the post therebetween and substantially abutting each other, the remaining rolled edges of the panels terminating at the outer edges of the post, the end portions of said panels between said rolled edges being in said openings, and means securing the panels to the post.

THOMAS M. DANIEL.
